UNITED STATES PATENT OFFICE.

ALFRED MILLEMAN, OF TURTLE CREEK, PENNSYLVANIA.

DESIGN FOR A WINDOW-WEDGE.

52,828.

Specification for Design.

Patented Dec. 31, 1918.

Application filed November 3, 1917. Serial No. 200,049. Term of patent 7 years.

To all whom it may concern:

Be it known that I, ALFRED MILLEMAN, a citizen of the United States, residing at Turtle Creek, in the county of Allegheny and State of Pennsylvania, have invented a new, original, and ornamental Design for Window-Wedges, of which the following is a specification, reference being had to the accompanying drawing, forming part thereof.

Figure 1 is a plan view of my window-wedge, illustrating the ornamental design thereof.

Copies of this patent may be obtained for five cents each, by addressing the "Commissioner of Patents, Washington, D. C."

Figs. 2 and 3 are side and end views, respectively, showing my new design.

I claim:

The ornamental design for a window wedge, as shown.

In testimony whereof I affix my signature in the presence of two witnesses.

ALFRED MILLEMAN.

Witnesses:

JENNIE JONES,
R. CLEMENT WEBER.
